ASSIGNORS OF ONE-THIRD TO ARTHUR D. DAVIS, OF MOBILE, ALABAMA.

SAUSAGE-MACHINE.

1,171,549.

Specification of Letters Patent. Patented Feb. 15, 1916.

Application filed April 26, 1915. Serial No. 23,842.

To all whom it may concern:

Be it known that we, JOHN C. SMITH and SION A. DARNELL, citizens of the United States, and residents of Mobile, in the county of Mobile and State of Alabama, have invented certain new and useful Improvements in Sausage-Machines, of which the following is a specification.

Our invention is an improvement in sausage machines, and the invention has for its object to provide a machine of the character specified, adapted for simultaneously operating upon a series of rolls of sausage, of that type known as "wienerwurst" or the like for dividing the several rolls into links of a predetermined length, by subjecting the roll at predetermined points to a twisting movement on its long axis, whereby to divide the roll into links.

In the drawings, Figure 1 is a side view of a portion of the improved machine; Fig. 2 is a top plan view, with parts in section; Fig. 3 is a section on the line 3—3 of Fig. 1, looking in the direction of the arrows adjacent to the line; Fig. 4 is a longitudinal, vertical section through one of the operating tubes or casings, showing the parts in one position; Fig. 5 is a similar view to Fig. 4, showing the parts in another position; Figs. 6, 7 and 10 are sections on the line 6—6, 7—7 and 10—10, respectively, of Fig. 4, each view looking in the direction of the arrows adjacent to the line; Fig. 8 is a section on the line 8—8 of Fig. 5, looking in the direction of the arrow adjacent to the line; Fig. 9 is a view similar to Fig. 8, showing the parts in another position; and Fig. 11 is a detail side view of a portion of the operating mechanism.

The present embodiment of the invention comprises a table 1, of suitable size and suitably supported, having an opening 2, in which the operating mechanism to be later described, is arranged.

A sheet metal feed table 3 is arranged at one end of the opening, the said sheet metal being secured to the table at the opposite sides of the opening by screws 4 or the like, and the sheet is provided at its inner end and at each side with an extension 5, extending alongside the side of the opening, and having its inner edge flush with the edge of the opening, and each extension is secured to the table at its outer edge by the screws 5, before mentioned.

From an inspection of Fig. 3, it will be noted that the table is counter-bored or rabbeted on its upper face at each of the extensions 5 as indicated at 6, and each of the said rabbeted portions extends from near the inner end of the extension to a point beyond where the extension merges into the body of the sheet. These rabbeted portions 6, in conjunction with the extension 5, form guideways for receiving the opposite side edges of a sheet metal apron 7, which is arranged to move beneath the table 3 and to move in the guideways formed beneath the extensions 5.

The sausage rolls 8 to be operated upon, are fed over the feed table 3 and over the apron 7, in a manner to be later described, and the operating mechanism for operating upon the rolls is arranged within the opening 2. This mechanism in the present instance is arranged to operate simultaneously upon two rolls of sausage, but it is obvious that the machine may be arranged to operate upon any desired number of rolls.

Each of the rolls is fed into a tube or tubular casing 9, each of the said casings having a diameter slightly greater than that of the roll upon which it is to operate, and each of the said tubes is of a length to receive approximately two and one-half links into which the rolls are to be divided.

Each of the tubes 9 passes at its front end through an opening in a supporting plate 10, and a collar 11 is secured to each tube on the outer side of the plate 10 to prevent movement of the tube with respect to the plate in the opposite direction. Each of the tubes 9 is also reamed outwardly or beveled at its front end to permit the easy entrance of the sausage roll, and a gear wheel 12 is keyed to each tube on the inner side of the plate 10.

The tubes 9 are as before stated, arranged in series of two, a single series being shown in the present instance, and the gear wheels 10 of the series mesh with a gear wheel 13 arranged below and between the gear wheels 12 and secured to a shaft 14 by means of a key 15. The shaft 14 has the end adjacent to the plate 10 reduced and threaded, and the said end is passed through an opening in the plate 10, and is engaged by a nut 16 on the outer face of the plate to secure the shaft in place and prevent longitudinal movement thereof.

It will be obvious that when the shaft 14 is rotated under conditions to be presently described, the two tubes 9 will also be rotated in the same direction, and at the same speed. The plate 10 is provided with an upward extension 10^a intermediate its ends and approximately at its center, and the extension is extended inward, as shown in Figs. 4 and 5. The upper face of the extension forms a guideway for engagement by a slide plate 17 movable laterally of the tubes 9 on the guideway. This slide plate is provided with longitudinally extending slots 18 at its ends, and the slots are engaged by threaded stems 19 extending upwardly from the upper edge of the plate 10, and this stem is engaged by a nut 20 above the slide plate. Thus the slide plate is guided and limited in its movement on the extension of the plate 10, and the plate is provided intermediate its ends and at approximately its center with an upstanding wrist pin 21, which engages within a longitudinal slot 22 in one of the arms 23 of a rock lever to be later described, and comprising an arm 23, and an arm 24 extending at approximately a right angle with respect to the arm 23. The slide plate 17, as shown in Fig. 4, is rabbeted on its under face to fit the extension 10^a of the plate 10, and inside the plate 10 the slide plate is provided with a series of depending rack teeth or with a depending rack bar 25. The teeth of this rack bar 25 mesh with the teeth of a pinion 26 which is secured to a stub shaft journaled in the plate 10 transversely thereof, between the tubes 9.

The pinion is keyed to the shaft, as shown in Fig. 6, and on the opposite side of the plate 10 the stub shaft has a cross head 28 secured thereto. Links 29 are connected with the ends of the cross head intermediate the ends of the links, and the links are arranged parallel, as shown more particularly in Fig. 3, above and below the openings in the tubes 9. Each link 29 extends in both directions from the cross head toward the opposite ends of the plate 10, as shown in Fig. 3, and at their opposite ends the links are connected by cross heads 30 pivoted to the plate 10. It will be evident that when the cross head 28 is oscillated the links 29 will be moved toward or from each other, and they are held parallel by the cross heads 30, pivoted to the plate 10 and connecting the ends of the links. The cross heads 30 being freely movable with respect to the plate 10, serve merely to hold the bars or links 29 parallel with each other, and when the cross head 28 is moved as indicated in dotted lines in Fig. 3, the links or bars 29 will be moved toward each other, moving at the same time toward the centers of the tubes 9.

The operation of the said links or bars is shown more particularly in Figs. 4 and 5. In Fig. 5 the cross heads 28 and 30 are in

normal vertical position. When, however, the slide plate 17 is moved toward the left of Fig. 3, the stub shaft 27 will be rotated, through the engagement of the rack bar 25, with the pinion 26, in a direction to swing the upper end of the cross head 28 to the left of Fig. 3. The cross heads 30 move in unison with the cross head 28 and the links 29, which are in fact compressing links, are moved together on the sausage roll, as shown in Fig. 4.

The links are moved by the rock lever 23-24, the said lever being pivoted on a pivot pin 31, which extends upwardly from an arch bracket 32 which extends transversely of the tubes 9. This arch bracket 32 is provided at each end with a foot 33, and each of the feet is curved transversely to fit over a nipple 34 extending rearwardly from the lower side edge of the plate 10, and the feet are secured to the extensions by means of screws 35 or the like. Each of these extensions 34 of the plate 10 is mounted to slide on a tubular guide 35, and said guides are supported below the table 1 at each side 90 of the opening 2.

Each guide is provided at its front end with a bracket plate 37, fitting the under face of the table 1, and secured thereto, as shown. From the bracket plate each of the guides extends rearwardly, to the opposite end of the opening 2. Here the end of the guide is received within a tubular extension or nipple 38, on a plate 39 secured to the table within the opening, and extending 100 above and below the opening. The plate 39 is, as shown in Fig. 1, bolted to angle brackets 40 secured to the under side of the table. The plate 10 and its integral extensions or bearing sleeves 34 together with the arch bracket 32, are mounted to move longitudinally of the guides 36, and they are moved by means of a pitman 41 which is pivoted at one end between a pair of laterally spaced lugs 42 on the plate 10, and at the opposite end to a wrist pin 43 on a disk or wheel 44 keyed to an operating shaft 45. The operating shaft is journaled in depending bearings 46 on the under side of the table 1, and it will be evident that when the said shaft is rotated, the pitman will reciprocate the plate 10 and the parts connected therewith.

A link or rod 47 is pivoted at one end to the arm 24 of the elbow lever 23-24, and the said link or rod is provided with a plurality of stops which are adjustable thereon. At the end remote from the elbow lever the link or rod passes through an opening in the upper end of the plate 39, and the stops 48 and 49 are mounted on the rod on opposite sides of the plate. These stops 48 and 49 are in the form of collars adjustable on the link or rod and held in adjusted position by a set screw 50. By loosening the set screw pertaining thereto, either stop may

be adjusted to the desired position, and may be secured in such position by tightening the set screw.

When the plate 10 and connected parts are reciprocated as above mentioned, it will be evident that at one end of its travel the stop 48 will engage with the plate 39, while at the other end of the travel of the plate 10, the stop 49 will engage with the plate. The stops 48 and 49 will engage the plate 39 near the end of the movement of the plate 10 in each direction. The plate 10 with its extensions 34, the arch bar 32 and connected parts, will be hereafter described for the sake of brevity as the carriage, and when the said carriage is moved toward the feed table 3, just before it reaches the end of its movement in this direction, the stop 49 will engage the plate 39, and will shift the slide plate 17 to cause the same to operate the mechanism connected therewith to close the compressing links 29 on the sausage roll. When the carriage moves toward the plate 39, just before it reaches the end of its movement in this direction, the stop 48 will engage the plate 39 and will cause the slide plate 17 to separate the compressing links 29 to release the roll.

Clamping mechanism is arranged in each of the tubes 9 for clamping the sausage roll, to constrain the roll to move with the tube when the carriage is reciprocated. The said clamping mechanism is constituted by a plate 51 arranged within the tube, and of approximately the same length as the tube. Each of the plates 51 is curved transversely to fit the tube 9, and each plate 51 is connected to the adjacent tube 9 by means of links 52, and each of the links 52 is arranged in a slot 53 in the tube 9. Each link is pivoted at its outer end to the tube, and at its inner end to the clamping plate.

The tube has a pair of spaced bearing lugs to which the outer end of each link is pivoted, and the clamping plate has a similar pair of lugs for connection with the inner end of the link. The tubes 9 are of such diameter that the sausage will move freely through them, and the clamping plates are of a width to cover approximately one-third the periphery of the roll.

The clamping plates are mounted at the tops of the tubes, and each plate is provided between the supporting links 52 with a pair of cams 54 and 55. The cams extend through slots in the tube 9, and they are arranged in longitudinal alinement with respect to the tube 9. The cams are adapted to be engaged by operating rings 56 mounted on the tubes 9, between the cams. Each of the operating rings or sleeves 56 has its forward end, that is, the end adjacent to the plate 10, tapering or conical, and the cam 55 has the face remote from the plate 10 undercut as shown, for engagement by

the tapering end of the ring, to lift the cam and clamping plate.

The opposite end of each sleeve or ring 56 is counter-bored as shown in Fig. 4, and the inner end of the counter-bored portion is inclined or tapered as indicated at 57. This incline is adapted to ride upon that face of the cam 54 adjacent to the plate 10, and said face is inclined, as will be seen from an inspection of Figs. 4 and 5, to coöperate with the incline 57, to move the clamping plate downward to the sausage roll.

Each of the rings or sleeves 56 has an annular groove 58, and the groove of each ring is engaged by the arm 59 of a fork on the end of a cross head 60. This cross head is arranged between the tubes 9, with the forks extending in opposite directions, and the arms of each engage the groove of the adjacent sleeve or ring. The cross head is connected to one end of a rod 61, the said end being threaded and passed through an opening in the cross head, and nuts 62 are threaded on the rod on opposite sides of the cross head to hold the same in adjusted position. The rod extends from the cross head toward the plate 39, and through the opening in the plate, and the said end of the rod has a head 63 for engagement by the plate to move the rod. The movement of the sleeves or rings 56 is very slight, and at the end of the movement of the carriage in each direction. This movement is just sufficient to cause the sleeve or ring to move from the position of Fig. 4 to that of Fig. 5.

In Fig. 4 the ring is shown as engaging the cam 54 to cause the plate 51 to clamp the sausage roll. The shaft 14 is arranged to be rotated by the reciprocation of the carriage. It will be noted that the said shaft has the end adjacent to the plate 39 provided with a spiral groove 64, and this end of the shaft passes through a ratchet wheel 65 which is journaled on the inner face of the plate 39 and rotatably held in contact with the plate by means of a nut 66. The ratchet wheel has a tubular hub which passes through an opening in the plate 39, and the nut 66 engages the hub on the opposite side of the plate 39 from the ratchet wheel.

The ratchet wheel has an inwardly extending lug 67 which engages the groove 64, as shown more particularly in Fig. 10, and the ratchet wheel is engaged and is held from reverse movement by a pawl 68 pivoted to the plate 39 and normally pressed into engagement with the wheel by a spring 69. It will be obvious that when the shaft 14 moves through the ratchet wheel in one direction, the wheel may be rotated with the shaft. When, however, the shaft moves in the opposite direction, the wheel is held from rotation by the pawl, and the shaft is rotated, thus causing the shaft to rotate the gear wheel 13.

The feed apron 7 is connected to the carriage, the said plate having a downwardly offset portion 70 which is secured to the outer face of the plate 10 by means of screws 71 or the like. Thus when the carriage is reciprocated the feed apron will move therewith. The feed apron 7 provides a support for the sausage roll whatever the position of the carriage. Were no support provided, when the carriage moved away from the feed table 3, that portion of the sausage roll between the carriage and the inner end of the feed table would be unsupported. The feed apron, however, being connected with the carriage and moving therewith, provides a support for the sausage roll, whatever the position of the carriage. The outer end of the apron moves beneath the feed table, and the apron is of sufficient length to cover the space between the inner end of the feed table and the carriage, whatever the position of the carriage.

The operation of the machine is as follows: The sausage in rolls is fed to the tubes 9. As the shaft 45 is rotated, the carriage will be reciprocated, moving from the position shown in Fig. 4, to the opposite end of its travel. As the carriage moves toward the plate 39, the sausage is operated upon, while on the return movement the sausage roll is released. As the carriage moves toward the feed table 3, the sausage roll is released, so that no impediment is offered to its passage through the tubes 9. Just as the carriage reaches the end of its movement toward the feed table 3, the stop 49 engages the plate 39 and swings the elbow lever 23-24 in a direction to cause the slide plate to rotate the stub shaft 27 toward the left of Fig. 3. This movement causes the compressing links 29 to move toward each other and toward the sausage roll, and said links grasp the sausage roll between them, as shown in Fig. 4.

It will be noticed from an inspection of Fig. 4 that the adjacent edges of the said links are rounded to prevent injury to the covering of the sausage, and they hold the sausage during the twisting thereof, to provide a distinct division between the adjacent links. Just after the link 47 is shifted, as above noted, the link 61 will be shifted, through the engagement of the head 63 with the plate 39. This movement will cause the cam rings or sleeves 56 to be moved relative to the tubes 9, and toward the cams 54. The inclined surface 57 of the cam sleeve will ride up the inclined face of the cam 54, and will move the clamping plate 51 downwardly to clamp the sausage. The sausage is now clamped in the tube, and is also held between the compressing links at a point where it desired to form a division between two links, and the carriage is ready to move in the opposite direction, on its

operative stroke. The carriage now begins to move toward the plate 39, and since the ratchet wheel 65 is held from turning by the shaft 68, the shaft 14 will be rotated in the direction of the arrow on the said shaft 70 in Fig. 4. The gear wheel 13 will rotate and will rotate the gear wheels 12 at the same speed and in the same direction. These wheels are connected to the tubes 9, and said tubes, together with the sausage rolls which are clamped to the tubes, will be rotated. All of that portion of the sausage roll within the tube 9 which is held by the plate 51 will be rotated with respect to that portion which is on the feed apron 7, and since the sausage is held between the links 29, a neck 8^a will be formed between this new link and the body of the sausage roll. The rotating movement of the sausage continues throughout the operative stroke or reciprocation of the carriage. Just before the carriage reaches the end of its movement toward the plate 39, the stop 48 engages said plate and the link 47 is shifted in a direction to move the links 29 away from each other, as shown in Fig. 5. At the same time, or shortly thereafter, the adjacent ends of the cam sleeves 56 engage the inner face of the plate 39, and the said cam sleeves are moved toward the cams 55.

The beveled ends of the sleeves engage the undercut faces of the cams, thus lifting the clamping plates and releasing the sausage rolls. The carriage is now ready for the return movement, and as it moves, the ratchet wheel 65 is free to rotate, and does rotate, so that the shaft 14 is not affected. The sausage roll is held from movement by that portion which has already been formed into links, and by that portion which has not yet been touched, and on the return stroke of the carriage the rolls will move through the tubes. When the carriage reaches the end of its movement toward the feed table 3, the compressing or clamping links 29 will be operated to clamp the rolls at a new point, and the clamping plates 51 will be operated to clamp the rolls in the tubes.

Each time a length of sausage sufficient to form a link will be marked off from the body of the roll, and will be twisted to form the neck 8^a between the link and the body of the roll. The length of the links formed depends upon the extent of the reciprocation of the carriage, and it will be evident that to provide other series of tubes will require only mechanical changes such as will be obvious to those skilled in the art. The carriage moves on the guides 36 and the operation is entirely automatic.

We claim:

1. A sausage machine, comprising a feed table, a carriage movable longitudinally thereof, guides for the carriage, means for

reciprocating the carriage, a tubular casing journaled longitudinally of the carriage, clamping mechanism in the casing for clamping a sausage roll within the same, 5 means operated by the movement of the carriage away from the feed table for rotating the casing and releasable therefrom on the reverse movement of the carriage, means controlled by the movement of the carriage 10 in opposite directions for operating the clamping mechanism to clamp the roll when the carriage moves away from the feed table and release the roll when the carriage moves toward the table, a pair of clamping links 15 mounted on the carriage at the front end of the casing for movement toward and from each other to clamp the roll, and means controlled by the movement of the carriage in opposite directions for moving the links toward and from each other. 20

2. In a sausage machine, comprising a reciprocating carriage and a tubular casing journaled longitudinally of the carriage for receiving a sausage roll, and having clamping mechanism for clamping the roll to the casing, means for rotating the casing when the carriage moves in one direction, said means comprising a gear wheel on the tube, a shaft journaled parallel with the tube and 25 having a gear wheel meshing with the gear wheel thereon, said shaft having a spiral groove, a ratchet wheel on the shaft and having a lug for engaging the groove, a fixed support upon which the ratchet wheel 30 is journaled, and a pawl engaging the wheel to prevent reverse movement thereof.

3. In a sausage machine, comprising a reciprocating carriage and a tubular casing journaled longitudinally of the carriage for receiving a sausage roll, and having clamping mechanism for clamping the roll to the casing, means for rotating the casing when the carriage moves in one direction, said means comprising a gear wheel on the tube, a shaft journaled parallel with the tube and 40 having a gear wheel meshing with the gear wheel thereon, means in connection with the shaft for rotating the shaft when the carriage moves with the roll clamped and for 45 releasing the shaft when the carriage moves in the opposite direction.

4. In a sausage machine, a tubular casing adapted to receive a sausage roll, said casing being supported for rotating movement and 55 for longitudinal movement, means for guiding the casing in its longitudinal movement, means for reciprocating the casing, means within the casing for clamping the sausage roll to the casing, means operated by the 60 movement of the casing in opposite directions for controlling the clamping mechanism to clamp and release the roll, means controlled by the movement of the casing when the sausage is clamped to rotate the 65 casing and releasable from the casing when

the casing moves in the opposite direction, means at the end of the casing for separating a link from the roll, said separating means comprising a pair of parallel links mounted for movement toward or from each other, and means controlled by the movement of the casing in opposite directions for operating the links. 70

5. In a sausage machine, a tubular casing adapted to receive a sausage roll, said casing 75 being supported for rotating movement and for longitudinal movement, means for guiding the casing in its longitudinal movement, means for reciprocating the casing, means within the casing for clamping the sausage 80 roll to the casing, means operated by the movement of the casing in opposite directions for controlling the clamping mechanism to clamp and release the roll, means controlled by the movement of the casing 85 when the sausage is clamped to rotate the casing and releasable from the casing when the casing moves in the opposite direction, and means at the end of the casing for separating a link from the roll. 90

6. In a sausage machine, a tubular casing adapted to receive a sausage roll, said casing being supported for rotating movement and for longitudinal movement, means for reciprocating the casing, means within the casing 95 for clamping the sausage roll to the casing, means operated by the movement of the casing in opposite directions for controlling the clamping mechanism to clamp and release the roll, and means controlled by the movement of the casing when the sausage is clamped to rotate the casing and releasable from the casing when the casing moves in the opposite direction. 100

7. In a sausage machine, a rotatable and longitudinally movable casing adapted to receive a sausage roll, means within the casing for clamping the roll to the casing, and means controlled by the movement of the casing longitudinally in one direction for 105 rotating the casing, said rotating means being releasable from the casing when the casing moves in the opposite direction. 110

8. In a sausage machine, a rotatable and longitudinally movable casing adapted to receive a sausage roll, means within the casing for clamping the roll to the casing, and means controlled by the movement of the casing longitudinally in one direction for 115 rotating the casing. 120

9. In a sausage machine, a rotatable and longitudinally movable casing for receiving a sausage roll, means for rotating the casing, to twist the sausage roll, and a connection between the said rotating means and the casing for releasing the casing from the rotating means when the casing moves in one direction. 125

10. In a sausage machine, a rotatable and a longitudinally movable casing for receiv- 130

ing the roll, means for rotating the casing, a connection between the said means and the casing for releasing the said means from the casing when the casing moves in one direction, and means within the casing for clamping the sausage roll thereto and controlled by the movement of the casing in opposite directions.

11. In a sausage machine, a casing for receiving the roll, a support in which the casing is rotatable and longitudinally movable, means for reciprocating the casing, and means controlled by the movement of the casing in opposite directions for clamping 15 the sausage roll to the casing.

12. In a sausage machine, a casing for receiving the sausage roll, a support in which the casing is mounted for rotating and longitudinal movement, means for clamping 20 the roll to the casing controlled by the movement of the casing in opposite directions, means controlled by the movement of the casing in one direction for rotating said casing, and means controlled by the 25 movement of the casing in the opposite direction for separating a link from the roll.

13. In a sausage machine, a casing for receiving the sausage roll, a support in which the casing is mounted for rotating and longitudinal movement, means for clamping 30 the roll to the casing, controlled by the movement of the casing in opposite directions, and means controlled by the movement of the casing in one direction for rotating said casing.

14. In a sausage machine, a casing for receiving the sausage roll, and a support in which the casing is mounted for rotating and longitudinal movement, and means for 40 clamping the roll to the casing controlled by the longitudinal movement of the casing in opposite directions.

15. In a sausage machine, a casing for receiving the sausage roll, a support in which 45 the casing is mounted to rotate and to move longitudinally, and means at the inlet end of the casing for separating the sausage into links, and controlled by the movement of the casing in opposite directions.

50 16. In a sausage machine, a casing mounted to rotate longitudinally, means for rotating the casing and controlled by the longitudinal movement of the casing in one direction, and means for separating a link 55 from the roll, controlled by the longitudinal movement of the casing in the opposite direction.

17. In a sausage machine, a casing mount-

ed to move longitudinally and to rotate, and adapted to receive the roll, means for rotating the casing controlled by the longitudinal movement of the casing in one direction, and means for clamping the roll to the casing, controlled by the movement of the casing in the said direction to clamp the 65 roll and to release the roll when the casing moves in the opposite direction.

18. In a sausage machine, a casing for receiving the sausage roll and mounted to move longitudinally and to rotate, a clamping plate within the casing for clamping the roll to the casing, a swinging connection between the plate and the casing to move the plate toward and from the roll as the plate swings, and means for swinging 70 the plate in opposite directions controlled by the longitudinal movement of the casing.

19. In a sausage machine, a casing for receiving the roll of sausage, clamping bars 80 movable toward and from each other at one end of the casing, and means controlled by the movement of the casing longitudinally in opposite directions for moving the bars into and out of clamping position.

20. In a sausage machine, a casing for receiving the roll of sausage, and mounted to move longitudinally, a shaft parallel with the casing and moving therewith and having a spiral groove, a ratchet wheel encircling the shaft and having a lug engaging 90 the groove and journaled on a fixed support, a pawl engaging the ratchet wheel to prevent movement thereof in one direction, and a driving connection between the shaft and the casing.

95 21. In a sausage machine, a feed table, a casing at one end of the table and adapted to receive a sausage roll, a sliding connection between the feed table and the casing, means for moving the casing longitudinally, 100 a feed apron connected with the casing at the end adjacent to the table and adapted to extend beneath the roll, means controlled by the movement of the casing in opposite directions for clamping the roll to the casing and releasing it therefrom, means controlled by the movement of the casing for separating a link from the roll, and means controlled by the movement of the casing away from the table for rotating the casing. 110

JOHN CALVIN SMITH,
SION ARRINGTON DARNELL.

Witnesses as to Sion Arrington Darnell:
ROBERT H. McCONNELL,
ALBERT N. STOKES.
